UNITED STATES PATENT OFFICE.

ANTHONY PULBROOK, OF LONDON, ENGLAND.

INFLATABLE TIRE.

SPECIFICATION forming part of Letters Patent No. 601,325, dated March 29, 1898.

Application filed November 6, 1895. Serial No. 568,099. (No specimens.) Patented in France April 3, 1894, No. 237,516; in Belgium April 6, 1894, No. 109,338, and in England August 8, 1894, No. 15,172.

To all whom it may concern:

Be it known that I, ANTHONY PULBROOK, solicitor, a subject of the Queen of Great Britain, residing at 8 Unwin Mansions, Queens Court Gardens, West Kensington, London, in the county of Middlesex, England, have invented certain Improvements in Inflatable Tires and Covers for the Same, (for which I have obtained patents in the following countries: Great Britain, No. 15,172, dated August 8, 1894; France, No. 237,516, dated April 3, 1894, and Belgium, No. 109,338, dated April 6, 1894,) of which the following is a specification.

The outer tubes or coverings of inflatable tires are sometimes made of the skins of fishes or amphibious animals, thin leather—such as Wamba skin, deerskin, horse-hide, the grain part of pigskin, or other thick leather after the flesh part has been skived or split away—and other similar material. My present invention relates to a means or process for rendering such tubes or coverings air-tight and waterproof to prevent them from cracking, to

strengthen them, and to increase their wearing qualities. For this purpose I treat them with a thin solution of balata, which penetrates every part of the skin or other material, and when dry I treat the material again with the solution, and so on until the material is thoroughly impregnated with balata. The balata solution may be made with cold bisulfid of carbon or warm mineral naphtha; but I do not claim any particular method of making the solution, but use any known method.

I claim—

A material for use in the manufacture of pneumatic tires comprising skins, leather or similar material thoroughly impregnated with balata, substantially as described.

In witness heréof I have hereunto set my hand in presence of two witnesses.

ANTHONY PULBROOK.

Witnesses:

WILLIAM HENRY BECK,
STEPHEN EDWARD GUNYON.
